UNITED STATES PATENT OFFICE

93,910

DESIGN FOR A WATER FILTER

Raymond G. Camp, New Philadelphia, Ohio

Application February 23, 1934, Serial No. 50,825

Term of patent 14 years

To all whom it may concern:

Be it known that I, RAYMOND G. CAMP, a citizen of the United States, residing at New Philadelphia, in the county of Tuscarawas, and State of Ohio, have invented a new, original, and ornamental Design for a Water Filter, of which the following is a specification, reference being had to the accompanying drawing, forming part thereof, in which:

Figure 1 is a perspective view of the water filter looking at one side thereof, and

Figure 2 is a perspective view of the water filter looking at the opposite side thereof.

I claim:

The ornamental design for a water filter, as shown.

Signed at New Philadelphia, in the county of Tuscarawas, and State of Ohio, this 27th day of January, 1934.

RAYMOND G. CAMP.
